UNITED STATES PATENT OFFICE.

GEORGE E. BULL, OF MONESSEN, PENNSYLVANIA, ASSIGNOR TO PITTSBURGH STEEL COMPANY, OF PITTSBURGH, PENNSYLVANIA, A CORPORATION OF PENNSYLVANIA.

WIRE-HOOP MACHINE.

Application filed February 9, 1922. Serial No. 535,348.

To all whom it may concern:

Be it known that I, GEORGE E. BULL, a citizen of the United States, and resident of Monessen, in the county of Westmoreland 5 and State of Pennsylvania, have invented a new and useful Improvement in Wire-Hoop Machines; and I do hereby declare the following to be a full, clear, and exact description thereof.

10 My invention relates to a wire hoop machine.

In the accompanying drawing Fig. 1 is a plan view of my improved machine; Fig. 2 is a side elevation; Fig. 3 is an enlarged end 15 view partly broken away; Fig. 4 is an enlarged section through the feed-rolls and showing the manner in which the upper feed-roll is held in yielding engagement with the lower feed-roll; Fig. 5 is an enlarged detail, 20 partly in section, of the twister-gear; Fig. 6 is a section on the line 6—6, Fig. 5; Fig. 7 is an enlarged section on the line a—a, Fig. 1; Fig. 8 is an enlarged section on the line b—b, Fig. 1; Fig. 9 is an enlarged view of the knife 25 operating mechanism, the twister-gear being shown in section; Fig. 10 is a face view of the forming die; Fig. 11 is a face view of the forming die, showing the wire therein ready for twisting; Fig. 12 is a like view showing 30 the wire twisted and in position to be ejected therefrom; Fig. 13 shows the finished hoop; Figs. 14 and 15 show the portions of the 35 hoop showing the twist; Fig. 16 is a detail of the guiding blocks; Fig. 17 is a detail of the knife holder; Fig. 18 is a cross-section on the line 18—18, Fig. 10; and Fig. 19 is a detail of the ratchet and pawl device for operating the twister.

In the drawing, the numeral 2 designates 40 a suitable frame in which is mounted in suitable bearings the shaft 3, said shaft carrying the tight and loose pulleys 4 and 5 which may be connected up by a suitable belt to any source of power.

45 A spur gear 6 on the shaft 3 meshes with the gear-wheel 7 on the countershaft 8 mounted in suitable bearings in the frame. Connected to the countershaft 8 is the crank-arm 9, to the outer end of which is connected the pitman 10, the connection of said crank-arm being adjustable to provide for different lengths of throw of the pitman 10. The outer end of the pitman 10 is connected to the arm 11 mounted on the shaft 12. The

arm 11 carries the pawl 13 which is adapted 55 to engage the teeth of the ratchet-wheel 14 mounted on the shaft 12. In this manner an intermittent rotary motion is imparted to the shaft 12 to provide for the intermittent feed of the wire, as will more fully 60 hereinafter appear.

On the shaft 12 is the gear-wheel 15 which meshes with the spur-gear 16 on the shaft 17. The gear-wheel 18 on the shaft 17 meshes with the spur-gear 19 on the shaft 20. 65

The shaft 20 carries the lower feed-roll 21 which is preferably made in two parts, one part 22 having the gear-teeth 23 and the hub-portion 24. On the hub-portion 24 is mounted the disc 25 which is secured to the part 70 22 by screws 26 and has the peripheral grooves 27 formed therein to receive the wire designated by the numeral 28.

The upper feed-roll 29 is formed in two parts in the same manner as the lower feed- 75 roll, and the upper roll is driven by the teeth of the lower roll meshing with the gear-teeth of the upper roll.

The upper roll is yieldingly mounted in the following manner. Arms 30 are loosely 80 mounted on the shaft 17 and in the outer ends of said arms is the shaft 31 on which is loosely mounted the upper feed-roll. At the outer ends of the arms 30 are the projections 32 and 33 through which the eye-bolts 34 pass, the lower ends of said eye-bolts being connected to the studs 35 on the standards 36 mounted on the frame of the machine. Springs 37 encircle the bolts 34 and are interposed between the projections 32 85 and 33 and nuts 38 on said bolts. In this manner the upper feed-roll is held in engagement with the lower feed-roll with any desired pressure which can be controlled by adjusting the nuts 38. 90

95 By making the feed-rolls in the form above described, with the removable discs 25 when one of the peripheral grooves 27 has been worn so as not to properly hold the wire for feeding, said disc may be removed and reversed so as to bring the other groove into play, and in this way the life of the feed-rolls is prolonged.

100 The wire 28 passes first through suitable straightening rolls 39 before reaching the feed-rolls and after passing the feed-rolls the wire enters the guide 40, which has the removable cover or plate 41 held in place by

the screws 42. The guide 40 is made up of two sections 43 and 44, the section 44 having the flaring inlet 45 which guides the wire properly.

5 Just beyond the guide 40 is the knife 46 which is mounted in the holder 47 and said holder is adapted to move up and down in suitable guides 48. The knife-holder 47 is connected at its lower end to the crank arm 10 49^a on the shaft 49, which shaft is mounted to turn in its bearings 51. Connected to said shaft is the longitudinal arm 52 which is connected by the spring 53 to the frame at the point 54. The action of the spring 53 15 is to hold the knife normally out of the path of the wire. To operate the knife a cam 55 on the shaft 56 is adapted to engage the roller 57 on the arm 52, and as the arm 52 is advanced by the movement of said cam 20 the knife-holder 47 is drawn down and the knife severs the wire, as will more fully hereinafter appear.

The twister-gear 58 has the hub portions 59 resting in bearings 60 in the standards 25 61. This twister-gear, as illustrated in Fig. 5, has the teeth 62 which are engaged by teeth of the gear-wheel 63 mounted on the shaft 64. A bevel pinion 65 on the shaft 64 is engaged by the bevel-gear 66 on the 30 shaft 56. Secured to the outer end of the shaft 56 is the ratchet 67. A pitman 68 is connected to the crank arm 69 on the shaft 8, said pitman being provided with the turn-buckle 70 for the purpose of adjusting the 35 twister-gear in proper relation with adjustment of the wire feeding device. The outer end of the pitman 68 is connected to a crank 71 provided with a pawl 72 adapted to engage the ratchet 67 whereby an intermittent 40 rotary movement is imparted to the shaft 56 and through said shaft to the twister-gear 58.

The twister-gear 58 has the slot 73 formed therein, and within said slot is the hardened steel slide 74 which is secured to the gear by the screws 75. Said slide has the slot 76 formed therein to receive the wire. By attaching the slide to the gear in this manner, as the slide wears it may be readily 45 replaced.

Beyond the twister-gear is the gripping device which consists of the arm 78 pivotally mounted at 79. The lower end 80 of the gripper-arm 78 engages the wires and grips 55 them during the twisting operation. A spring 81 connected to the upper end of the arm 78 and to the post 82 normally holds the gripper out of operation, and the gripper is thrown into operation by the following mechanism.

A pusher 83 is mounted in a suitable guide 84, and to the outer end of the pusher 83 is connected the lever 83^a by the pin 83^b engaging the slot 83^c in said lever. The 60 lower end of lever 83^a is connected to the lug

83^d in the frame, and a roller 83^e on said lever is engaged by the cam 85 on the cam-shaft 86. This cam-shaft 86 is driven through a train of gears 86^a and 86^b from a gear 86^c on the shaft 87, said shaft connecting with the shaft 8 through a pair of bevel gears 88—89. The pusher 83 is provided with the hardened steel finger 90 which is secured in said pusher by the set-screw 90^a, and said finger may be adjusted therein as 75 may be found necessary to grip different sizes of wire.

The former 91 for shaping the wire into hoop-form is made up of the circular rim-portions 92 with the web-portion 93 which, 80 with the movable plates or retainers 93 and 95, forms the passage or guide-way 91^a in the former for giving the shape to the wire as it is fed thereto, as is clearly shown in Figs. 11, 12 and 18. To provide for the 85 stripping or ejecting of the hoop from the former, the plates 94 and 95 are made movable inwardly and outwardly. A lever 96 is pivotally mounted at its outer end by means of the pin 97 in the clevis 98 secured 90 to the movable plate 94. The lever 96 is slotted at 99 to receive the pin 97 to allow for the proper play of said lever. The inner end of the lever 96 is secured to the shaft 100. A second lever 101 is secured 95 to the shaft 100, and the outer end of said lever carries the roller 102, which is in the path of the cam 103, on the shaft 86, whereby when said cam engages said roller 102 the levers 101 and 96 are moved so that the 100 guide-plate 94 is lifted to the position shown in Fig. 12. In order to simultaneously withdraw the plates 95 to the position shown in Fig. 12, the said plates 95 are connected to the uprights 104 on the plate 94 by studs 105 105 engaging diagonal slots 106 in said uprights.

Secured to the plates 94 and 95 are the beveled lugs 107 which engage the hoop at three points, and which act, when the plates 110 94 and 95 are withdrawn in the position indicated in Fig. 12, to force said hoop outwardly to eject it from the former, as will more fully hereinafter appear.

A complementary plate 108 is provided to 115 act in conjunction with the guide 40, so as to direct the entering end of the wire into position to overlap the wire to provide for twisting, the position of the wire being indicated in Fig. 7, one overlapping portion 120 of the wire being shown in the guide 40 and the other in the recess 109 in the complementary plate 108. This plate 108 has the downwardly projecting portion 110 which moves in a guide 111. A lever 112 is pivotally connected to the guide 111, and is connected at its outer end to the downwardly extending portion 110 of the plate 108 by the screw 113 engaging the slot 114 in said lever 112. A spring 115 is connected to the 125 lever 112. A spring 116 is connected to the 130

lever 112 and to the guide 111. The other end of the lever 112 is pivotally connected to the plate 94, so that when said plate is lifted to the position indicated in Fig. 12 the lever 112 withdraws the complementary plate 108 to permit the ejection of the wire-hoop at that point.

Additional ejectors 116 are provided which have a longer throw than the ejector-lugs 107, so as to force the hoop out of the slot of the twister-gear a sufficient distance to clear all the parts and allow it to drop to a point below. These ejectors 116 are pivotally connected to the slide 117 moving in the guides 118. The slides 117 have the rollers 119 which are in position to be engaged by the ejector cams 120 on the cam shaft 86. To provide for the withdrawal of the ejectors 116, cams 121 on the gear 63 are provided, said cams being adapted to engage rollers 119.

The operation of the machine is as follows:

Power is applied to the shaft 3 and communicated therefrom to the operative parts of the machine. The wire 28 is fed to the straightening rolls 39, whence it passes to the feed rolls 21 and 29 and is delivered through the guide 40 and twister-gear 58 to the former 91. The wire is directed through the passage 91^a formed in said former by the undercut plates 94, 95 and the complementary plate 108. As the wire enters the recess 109 of the complementary plate 108 it is directed so as to overlap the rear end of the wire, and when the proper amount of wire has been fed the knife 46 is operated to cut the wire, the cam 55 engaging the roller 57 on the arm 52 so that the knife holder 47 is drawn down and the wire severed. The gripping device then comes into operation, whereby the arm 78 is forced into position to tightly grip the overlapping wires beyond the twister gear. This is accomplished by the cam 85 engaging the roller 83^c on the lever 83^a which forces the pusher 83 outwardly and operates the gripper arm 78. With the wires gripped in this manner the twister-gear then comes into operation and the wires are twisted, as indicated in Figs. 14 and 15.

As soon as the twisting operation is completed the ejecting mechanism is brought into play, and this is accomplished by the cam 103 engaging the roller 102 so that the lever 96 is moved to raise the plate 94, and thereby to withdraw the plates 95 and 108. By the movement of the plates 94 and 95 the ejector lugs 107 act to move the wire-hoop outwardly from the former, as clearly shown in Fig. 18, and at the same time the cams 120 engage the rollers 119 on the slides 117 so that the ejectors 116 are advanced and force the hoop outwardly beyond the slot of the twister-gear, so that the hoop is free to

fall to a point below and free from the machine without requiring anyone to lift it from the former.

What I claim is:

1. In a machine for forming hoops, the combination of a former, means for feeding the wire thereto, means for severing the wire, means for twisting the overlapping wire and automatic mechanism for positively ejecting the hoop entirely from said former.

2. In a wire hoop machine, the combination of a former, means for feeding wire thereto, means for cutting the wire, means for twisting the overlapping wire, said former being in a plane at an angle to the horizon, and means for ejecting the hoop laterally from said former.

3. In a wire hoop machine, the combination of a former, means for feeding the wire thereto, means for cutting the wire, means for twisting the overlapping portions, said former being arranged in a vertical position, and means for ejecting the hoop laterally from said former.

4. In a wire hoop machine, the combination of a former having a guideway, means for feeding the wire thereto, means for severing the wire, means for twisting the overlapping portions, movable retainers on said former, and means for withdrawing said retainers simultaneously to permit of the wire being removed from said former.

5. In a wire hoop machine, the combination of a former, means for feeding wire thereto, means for cutting the wire, means for twisting the overlapping portions of said wire, a movable retaining plate at the bottom of said former, end plates connected to said movable plate, means for moving said main plate and said end plates simultaneously.

6. In a wire hoop machine, the combination of a former, means for feeding wire thereto, means for cutting the wire, means for twisting the overlapping portions of said wire, a retaining plate at the bottom of said former, end retaining plates having studs thereon engaging diagonal slots formed in said main retaining plate, and means for withdrawing said main retaining plate.

7. In a wire hoop machine, the combination of a former, means for feeding wire thereto, means for cutting the wire, means for twisting the overlapping portions of said wire, movable retaining plates, means for moving inwardly said plates, and ejecting means carried by said plates.

8. In a wire hoop machine, the combination of a former, means for feeding wire thereto, means for cutting the wire, means for twisting the overlapping portions of said wire, movable retainer plates on said former, means for withdrawing said retainer plates simultaneously, and beveled

lugs on said plates adapted to engage the wire to eject it from said former.

9. In a wire hoop machine, the combination of a former, means for feeding wire thereto, means for cutting the wire, means for twisting the overlapping portions of said wire, movable retainer plates on said former, a lever connected to one of said plates, connections between one of said plates and the other plates, whereby when said first plate is withdrawn said other plates are withdrawn, a lever connected to the main plate and connections between said lever, and a cam whereby when said cam engages said lever said plates are withdrawn.

10. In a wire hoop machine, the combination of a former, means for feeding wire thereto, means for cutting the wire, means for twisting the overlapping portions of said wire, means for holding the wire on said former, means for withdrawing said holding means, and means for ejecting the wire completely from said former.

11. In a wire hoop machine, the combination of a former, means for feeding wire thereto, means for cutting the wire, means for twisting the overlapping portions, means for retaining the wire in said former, means for withdrawing said retaining means, ejectors at a plurality of points, and means for moving said ejectors outwardly to eject the wire completely from said former.

12. In a wire hoop machine, the combination of a former, means for feeding wire thereto, means for cutting the wire, means for twisting the overlapping portions of said wire, means for retaining the wire in said former, means for withdrawing said retaining means, ejectors adapted to engage said wire at a plurality of points, cams, and connections between said cams and said ejectors, whereby said ejectors are advanced and withdrawn.

13. In a wire hoop machine, the combination of a former, means for feeding wire thereto, means for cutting the wire, a twister head having a slot therein to receive the overlapping portions of the wire, a gripper for holding the overlapping portions of the wire, means for retaining the wire in said former, means for withdrawing said retain-

ing means, and ejecting means for ejecting the wire completely from said former and from said slotted twister head.

55

14. In a wire hoop machine, the combination of a former, means for feeding the wire thereto, means for cutting said wire, means for twisting said wire at the overlapping portions, means for retaining the wire on said former comprising a guide for directing the entering end of said wire into overlapping position with reference to the other portion of said wire, and means for withdrawing said guide.

65

15. In a wire hoop machine, the combination of a former, means for feeding wire thereto, means for cutting the wire, means for twisting the overlapping portions of the wire, movable retaining means for holding the wire on said former, means for withdrawing said retaining means, and a movable guide for directing the entering end of said wire into overlapping position with reference to the other portion of the wire, and connections between said movable guide and said retaining means, whereby all are withdrawn at the same time.

70

16. In a wire hoop machine, the combination of a former, means for feeding wire thereto, means for cutting the wire, means for twisting the overlapping portions, a guide for delivering the wire to said former, a complemental guide operating in conjunction with said first-named guide adapted to guide the entering end of the wire into overlapping position, and means for withdrawing said complemental guide.

75

17. In a wire hoop machine, the combination of a former, means for feeding the wire thereto, means for cutting the wire, means for twisting the overlapping portions, a pivotally mounted gripping finger adapted to engage the overlapping portions, a pusher adapted to engage said finger, a cam, and connections between said cam and said pusher for advancing the same.

80

In testimony whereof I, the said GEORGE E. BULL, have hereunto set my hand.

GEORGE E. BULL.
